TELEPHONE CALLING DIAL

Cecil C. McCain, Glen Ellyn, Ill., assignor to
 Western Electric Company, Incorporated, New
 York, N. Y., a corporation of New York

Application February 4, 1947, Serial No. 726,256

6 Claims. (Cl. 179—90)

1

This invention relates to telephone calling devices and more particularly to dial type telephone calling devices commonly used in automatic telephone systems.

An object of this invention is to provide a telephone calling device of improved construction.

A particular feature of the invention is the provision of a one-way driving connection between the dial and a spring driven, governor-controlled drive wheel of the pulsing mechanism, which driving connection permits the dial to positively rotate the drive wheel in unison therewith when the dial is rotated in one direction to dial a digit and which permits a faster rotary movement of the dial relative to the governor-controlled spring actuated drive wheel in a reverse direction.

Another feature provides for locking the dial in its starting position when the dial has been manually returned to that position in advance of the return to its normal starting position of the drive wheel of the pulsing mechanism and provides means for rendering the locking means ineffective upon the return to its normal starting position of the drive wheel of the pulsing mechanism.

A further feature of the invention provides means for adjusting the motor spring to vary the torsional force applied to the drive wheel and which adjusting means is accessible upon the removal of the dial so that the torsional force may be increased or decreased from the front of the calling device after the dial has been removed.

These and other features of the invention will be more fully understood from the following description thereof when considered in connection with the accompanying drawings illustrating a preferred embodiment of the invention in which

Fig. 1 is a front elevational view of a calling device;

Fig. 2 is an enlarged rear elevational view of the calling device in which the pulsing contact springs and the cam for actuating same are shown in one position;

Figs. 3 and 4 are detailed views of the pulsing contacts and the actuating cam shown in different positions;

Figs. 5 and 6 are vertical sectional views through the calling device taken on the lines 5—5 and 6—6, respectively, of Fig. 2;

Fig. 7 is a detail plan sectional view through the device taken on the line 7—7 of Fig. 10;

Fig. 8 is a fragmentary elevational view of a portion of the device showing the governor for controlling the rate of pulse transmission;

Fig. 9 is an enlarged detail sectional view of the

2

pulsing contact springs and the actuating mechanism thereof as viewed from the front and taken on the line 9—9 of Fig. 6;

Fig. 10 is a vertical sectional view of the device taken on the line 10—10 of Fig. 5 showing the device with the number plate removed and in which members, comprising the driving connection between the dial and the driving wheel, are shown in their normal or starting position and with a stop and a latching member associated therewith;

Fig. 11 is a detail plan sectional view showing the driving connection between the dial and the rotatable drive wheel taken on the line 11—11 of Fig. 10;

Figs. 12 and 13 are detail views of a portion of the device illustrating various positions of the members comprising the driving connection between the dial and the wheel and their relation to the stop and latching members associated therewith;

Fig. 14 is a fragmentary vertical sectional view of the device taken on the line 14—14 of Fig. 5 and in which is shown the means for adjusting the spring to vary the tension on the wheel; and

Fig. 15 is a detail sectional view taken on the line 15—15 of Fig. 10 showing the spring adjusting members.

30 The calling device as illustrated in the drawings, particularly Figs. 2, 5, 6 and 10, comprises generally a housing or casing 20 having a centrally disposed bearing member 22 fixed thereto for rotatably supporting a finger wheel or dial 24

35 and a driving wheel 26 of a gear train, which wheel is stressed for rotation in a counter-clockwise direction, as viewed from the front by a torsion motor spring 28. The dial 24 is operatively connected to the driving wheel 26 through a

40 driving connection 30 (Figs. 5 and 11), which permits the imparting of rotary movement to the driving wheel by the dial upon rotation in a clockwise direction and permits of a relative faster movement of the dial with respect to the

45 driving wheel on the reverse movement thereof. The gear train is connected to a governor shaft 32 (Figs. 7, 10 and 11) for actuating a governor 34 and to a jack shaft 36, on which is mounted actuating means 38 for actuating the pulsing

50 contact springs 40 and 41.

The housing 20 has a cylindrical wall 42 (Fig. 5) projecting from a flat wall 43, which is centrally apertured to receive the bearing member 22, which, in turn, has a flange 44 fastened to the wall 43 of the casing by rivets 45 to secure the

bearing member 22 in position on the casing 20. The bearing member 22 is apertured at 46 to receive and rotatably support a shaft 47 having a flange 48 against which the dial 24 is positioned and which has non-circular portion 49 engaging in a similarly shaped aperture 50 in the dial. The dial 24 is locked on the shaft 47 by a nut 51 engaging the reduced threaded end 52 of the shaft with a washer 53 interposed between the nut and the disc. An arm 55, secured to the other end of the shaft 47 by a nut 56, serves to retain the shaft in the bearing member 22.

The driving wheel 26 comprises an annular gear 60 (Fig. 5) secured to a hub member 61, which is rotatably mounted on the exterior bearing surface 62 of the bearing member 22 and retained thereon against longitudinal movement by a shoulder 63 and a split retaining ring 64 fitting in an annular groove 65 in the bearing member 22. A pin 68 (Figs. 14 and 15) extending rearwardly from the vertical face of the hub member 61, engages in one of a plurality of apertures 69 of an annular adjusting member 70 rotatably mounted on the bearing member 22 in engagement with the hub member 61. An ear 71 (Figs. 5 and 14), formed on the adjusting member 70, engages one end 72 of the torsion motor spring 28, the other end 73 of which is anchored to the flange 44 of the bearing member 22. The spring 28 exerts a torsional force on the member 70 and the driving member 26, tending to rotate them in a counterclockwise direction, as viewed from the front, and the spring 28 is set under a predetermined initial tension. This tension can be adjusted by removing the dial 24 (Figs. 2 and 10) and inserting a tool through an arcuate aperture 74 in the hub member 61 into engagement with one of the apertures 69 of the adjusting member 70 accessible through the aperture 74 and moving the adjusting member axially to disengage it from the holding pin 68 and then rotating the member 70 to a position where the holding pin 68 is in alignment with the next aperture 69 and then allowing the spring 28 to move the adjusting member 70 axially into engagement with the hub member 61 and with the holding pin 68 engaging in another of the recesses 69. In this manner, the member 70 may be rotated step by step in either direction relative to the drive wheel 26 until the tension of the spring 28 has been adjusted to the desired amount.

The clutch or driving connection 38 (Figs. 5, 10 and 11) between the dial 24 and the driving wheel 26 comprises a driving member or pin 78, which is semi-circular in cross section and extends rearwardly from the flange 48 supporting the dial 24 and engages on its flat side 79 a pin 80 on the hub member 61. The spring induced rotary movement of the drive wheel 26 in a counterclockwise direction is transmitted by the pin 80 to the pin 78 and the dial 24 and is arrested when the dial 24 and the wheel 26 are in a predetermined position by the engagement of the pin 78 with a stop member 82 fixed to an annular supporting member or plate 83. The annular supporting plate 83 is mounted on the wall 43 of the housing 20 in spaced and parallel relation thereto by the arms 84 and screws 85. With this construction of drive connection between the dial 24 and the driving wheel 26, the dial may be rotated through a dialing movement in a clockwise direction, as viewed in Fig. 1, to impart a positive rotation through a similar arc to the driving wheel 26 and the drive connection per-

mits of a faster rotation of the dial relative to the driving wheel 26 in a counterclockwise direction. After a dialing movement in a clockwise direction of the dial 24, the dial may be manually returned to its starting position at a greater speed of rotation than that of the governor-controlled rotation of the driving member 26 without effecting the normal operation of the drive wheel 26.

To prevent the dialing movement of the dial 24 to initiate another digit dialing operation before the completion of the pulsing operation of the previous digit dialing operation, a latching means is provided and comprises a spring wire 88 (Figs. 10 and 11) anchored at 89 to the supporting plate 83. The end 90 of the member 88 is normally positioned in the path of movement of the pin 78 on the dial (Fig. 13) and, by engaging the flat surface 79 thereof, prevents rotation in a clockwise direction of the dial 24. The latching member 88 is engaged by the pin 80 on the wheel 26 and is displaced downwardly thereby to disengage the end 90 from the pin 79 when the driving wheel 26 returns to its normal starting position on completion of its pulsing cycle. With the drive wheel 26 and the pin 80 carried thereby in their normal starting position, the latching member 88 is ineffective to latch the dial 24 and the dial may be rotated in a clockwise direction to initiate a new dialing operation.

The gear 60 of the driving wheel 26 meshes with a pinion gear 93 on the jack shaft 36 (Figs. 6, 7, 10 and 14), to which is secured a gear 94, which meshes with the pinion gear 95 rotatably mounted on the governor shaft 32. The governor shaft 32 has one end thereof mounted in a bearing 97 (Figs. 5 and 7) carried by the supporting plate 83 and the other end mounted in a bearing 98 of the governor housing 99. A hub 101 (Fig. 7) of the gear 95 receives a clutch member comprising a closely wound helical spring 102, which also engages a peripheral surface of the hub 103 secured to a cross arm 104 of the governor 34. The cross arm 104 has pivoted thereto, as on pins 105-105, a pair of weight members 106-108, which are maintained in normal retracted position by springs 107-107 and which carry friction shoes 109-109 engageable with the inner surface of the drum 109 of the governor housing 99. The spring clutch member 102 permits the free rotation of the gear 95 in one direction and serves to connect the governor 34 to the gear 95 upon rotation of the gear in a reverse direction. Thus, the driving wheel 26 is disconnected from the governor 34 during its movement in a clockwise direction and is free to be rotated in a clockwise direction at any speed imparted to it by the dialing movement of the dial 24 and is effectively connected to the governor 34 upon its rotation in the reverse direction so that, as it rotates in a reverse or counterclockwise direction, its speed is controlled by the action of the governor 34. The dial, however, as previously mentioned, is free to be rotated at a faster speed if desired in a counter-clockwise direction to its normal starting position.

The jack shaft 36, which is rotated in response to the rotation of the drive wheel 26, is mounted in bearings 115 and 116 (Figs. 6 and 7), the former carried by the supporting plate 83 and the latter provided in a bracket 117 formed on the wall 43 of the housing 20. The pulsing or actuating means 38 (Figs. 3 and 4), mounted on the shaft 36, comprises a cam 118 fixed to the shaft, the cam having a pair of diametrically opposed

actuating lobes 119—119. The cam 118 engages a wear member 120 on the pulsing contact spring 41 (Fig. 2) to actuate the spring 41 as the cam 118 rotates. The contact springs 40 and 41, which are mounted in a molded insulated terminal block 122, are flexed to normally remain in contact with each other at their outer ends and are urged to the right, as viewed in Fig. 2, to follow the cam 118 as it rotates.

A fly member 123 (Figs. 6, 7, 9, 2 and 3), having a hub portion 124, is loosely mounted on the shaft 36 between the cam 118 and an enlarged portion 125 of the shaft 36. Extending radially from the hub portion 124 and in angular relation to each other, are arms 126 and 127 (Fig. 9). A spring friction member 128, mounted on the arm 127 by a pin 129, engages the enlarged portion 125 of the shaft 36 in a groove 130 therein and frictionally connects the fly member 123 to the shaft 36 for rotation therewith. The rotation of the fly member in one direction is limited by the engagement of the arm 126 with the bracket 117 (Fig. 3) and the rotation of the fly member in the other direction is limited by the engagement of the arm 127 with the governor housing 99 (Fig. 4). As the shaft 36 is rotated in the direction indicated by the arrow in Fig. 4, the fly member will be moved to the position shown in said Fig. 4 with the arm 126 projecting toward the contact spring member 40 and in the path of a laterally extending tab or extension 133 thereon (Figs. 7 and 9) so that, as the cam 118 continues to rotate and the contact springs 40 and 41 follow the cam to the right, as viewed in Figs. 2 and 4, the arm 126 will serve to stop the contact spring 40 after a short movement thereof and permit the separation of the contacts 40 and 41 as the member 120 rides off of the lobes 119 of the cam onto its low portions. Thus, while the shaft 36 is rotating in the direction indicated by the arrow in Fig. 4, the arm 126 of the fly member 123 and the cam 118 cooperate to effect the opening and closing of the contact springs 40 and 41 twice for each revolution of the shaft 36. When the shaft 36 is rotated in the opposite direction, that is, in the direction indicated by the arrow in Fig. 3, the fly member 123 is rotated to the position shown in Fig. 3, where the arm 126 thereof has been moved out of the path of the contact spring 40, thereby permitting the contact springs 40 and 41 to remain in contact with each other and move together through the oscillatory movements imparted to them by the cam 118. Thus, during the dialing movement of the dial and the driving wheel 26, that is, clockwise rotation, as viewed from Fig. 1, the fly member 123 acts to render the pulsing means ineffective and during the movement in a reverse direction of the drive wheel 26, the fly member serves to render the pulsing mechanism effective to produce pulses in response to the actuation of the contact springs 40 and 41 by the cam 118.

A pair of normally open contact springs 136 (Fig. 2) and a pair of normally closed contact springs 137, actuated by a roller 138 on the arm 55 of the shaft 47 in response to the dialing movement of the dial 24, are molded in the terminal block 122 and are connectible in the conventional manner to the substation apparatus for disconnecting the receiver and shunting the transmitter during the dialing operation.

An annular number plate 140 (Fig. 5), fitting within the annular wall 42 of the housing 20, forms a cover plate for the calling device and engages the supporting plate 83 and is locked in

position thereon by a split retaining ring 141 fitting in an annular groove in an annular flange 142 formed on the inner portion of the supporting plate 83. Within the annular flange 142, the annular space 143 surrounding the bearing 22 provides a clearance for the movement of the drive pin 78 on the flange 48 of the shaft 47 and also provides clearance for the insertion of a tool for engaging the spring adjusting member 70 for the purpose of adjusting the tension of the spring when the dial 24 has been removed. Numerals or other indicia 145 (Fig. 1) is printed or otherwise formed on the number plate 140 in predetermined position angularly spaced about the axis 15 of the dial and in alignment with finger holes 147 formed in the dial 24. A stop 148 overlying the dial 24 is carried by the housing 20 and serves to engage the finger of the person calling and limit the dialing movement of the dial 24.

When dialing a number, as, for example, the digit 9, the party calling inserts his finger in the finger hole 147 of the dial 24 opposite the numeral 9 and rotates the dial clockwise until his finger engages the stop 148, after which he removes his finger and the dial is returned to its original starting position, as shown in Fig. 1. As the dial 24 is rotated in a clockwise direction during the dialing movement, the drive pin 78 carried thereby, through its engagement with the pin 80 on the drive wheel, imparts a rotary movement to the drive wheel 26 equal in length to and in unison with the movement of the dial 24. The rotation of the drive wheel 26 causes the rotation of the cam shaft 36 and the cam 118 and the shifting of the fly member 123 carried thereby and effects the movement of the pulsing springs 40 and 41. The rotation of the shaft 36 during the dialing movement of the dial 24 is in such a direction as to cause the fly member 123 to be moved 30 into the position shown in Fig. 3, in which position of the fly member 123 the pulsing springs 40 and 41 are rendered ineffective and follow the contour of the cam 118 and are oscillated thereby with the contacts maintained in engagement with each other. Consequently, no pulses are being produced during the dialing or clockwise movement of the dial 24. The rotation of the drive wheel 26 during the dialing movement imparts rotation to the governor shaft 2 through the gears 93, 94 and 95, which rotation of the governor shaft 32 is not transmitted to the governor because of the action of the clutch member 102, which, as hereinbefore stated, serves to transmit rotation to the governor only when the shaft 45 rotates in the opposite direction.

At the end of the dialing movement, when the finger of the person dialing is removed from the dial, the motor spring 28 causes the drive wheel 26 to be returned to its starting position and, 50 through the engagement of the pin 80 carried thereby with the drive pin 78 on the dial, the dial 24 is rotated with the drive wheel 26 to its normal starting position. During the counter-clockwise movement of the drive wheel 26, the governor 34 is connected to the drive and serves to govern the speed of rotation and the rate of pulse transmission. The rotation of the shaft 36 during the return movement of the drive wheel 26 is 55 in the direction to cause the fly member 123 carried thereby to be moved into the position shown in Fig. 4 and acts to hold the pulsing spring 40 substantially in a fixed position so that the cam 118, during the rotation of the shaft 36, acts to reciprocate the contact spring 41 into and out of

contact with the spring 40 and cause the production of a series of pulses.

Should the person dialing, at the end of a dialing movement, decide to manually return the dial 24 at an increased rate of speed substantially faster than that of the governor controlled movement of the dialing wheel 26, with the intention of speeding up the dialing operations, the dial 24 is free to be rotated to its starting position without in any way affecting the counter-clockwise rotation of the governor controlled drive wheel 26 of the pulsing mechanism. When the dial 24, after first having been rotated in a clockwise direction, is rapidly returned to its normal starting position in advance of the driving wheel 26, the drive pin 78, rotating with the dial, engages the side of the latching member 88, moves it out of the way as the pin 78 passes, and permits it to return to its normal unflexed position with its end 90 in the path of and in substantial engagement with the face 70 of the pin 78, as indicated in Fig. 13. The latching member 88, in this position, serves to latch the dial 24 in its starting position until the pulsing portion of the cycle has been completed and the wheel 26 has returned to its normal starting position, during the final portion of the movement of which the pin 80 carried by the wheel 26 engages the latching member 88 and moves it out of its latching relation with respect to the drive pin 78. It will thus be seen that the dial 24, when returned to its starting position before the completion of a pulsing portion of the cycle of operation, is latched in its starting position and cannot be rotated to initiate another digit dialing operation until the previous pulsing cycle has been completed.

What is claimed is:

1. In a telephone calling device having pulsing contacts and means for actuating said pulsing contacts including a rotatable wheel, the combination with said rotatable wheel of a bearing for rotatably supporting said wheel, housing means for substantially enclosing said actuating means and through which a portion of the wheel is accessible, an annular adjusting member encircling the bearing member and engaging a portion of said wheel, a motor spring encircling said bearing member for rotating said wheel in one direction and having one end thereof fixed relative to the housing and the other end connected to the adjusting member, and means on said adjusting member and said wheel for making an interlocking non-rotatable engagement of said adjusting member with said wheel in any one of a plurality of angular positions, said wheel having an opening therein through which said adjustable member is accessible whereby a tool may be inserted through the opening into engagement with said adjustable member to adjust it relative to the wheel.

2. In a telephone calling device having pulsing contacts and means for actuating said pulsing contacts including a rotatable wheel, the combination with said rotatable wheel of a bearing for rotatably supporting said wheel, housing means for substantially enclosing said actuating means and through which a portion of the wheel is accessible, an annular adjusting member encircling the bearing member and engaging a portion of said wheel, a motor spring encircling said bearing member for rotating said wheel in one direction and having one end thereof fixed relative to the housing and the other end connected to the adjusting member, and means on said adjusting member and said wheel for making an interlock-

ing non-rotatable engagement of said adjusting member with said wheel in any one of a plurality of angular positions, said wheel having an opening therein through which said adjustable member is accessible whereby a tool may be inserted through the opening into engagement with said adjustable member to adjust it relative to the wheel.

3. In a telephone calling device having pulsing contacts and means for actuating said pulsing contacts including a rotatable wheel, the combination with said rotatable wheel of housing means substantially enclosing said actuating means and including a front wall having a central aperture therein, a removable dial on the outside of said housing operatively associated with said wheel and concealing said aperture in said front wall, bearing means carried by said housing means for supporting said wheel and said dial for rotation about a common axis extending through the aperture in the front wall, an annular adjusting member encircling said bearing means and axially movable thereon into engagement with said wheel, said wheel and said adjusting member having interfitting portions whereby the adjusting member may be received in any one of a plurality of non-rotatable interlocking positions with respect to said wheel, and a motor spring for rotating said wheel in one direction and having one end thereof fixed relative to the housing and the other end connected to said adjusting member, said wheel having an opening therein in alignment with the aperture in the front wall and through which the adjustable member is accessible when the dial is removed whereby a tool may be inserted through the aperture in the front wall and the opening in the wheel to engage and adjust the adjustable member relative to the wheel.

4. In a telephone calling device having pulsing contacts and means for actuating said pulsing contacts including a rotatable wheel, the combination with said rotatable wheel of a housing means substantially enclosing said actuating means and including a front wall having a central aperture therein, a removable dial on the outside of said housing operatively associated with said wheel and concealing said aperture in said front wall, bearing means carried by said housing means for supporting said wheel and said dial for rotation about a common axis extending through the aperture in the front wall, an annular adjusting member encircling said bearing means and axially movable into engagement with the rear face of said wheel, said adjusting member having a plurality of equally spaced apertures therein located equi-distant from the axis of rotation of said wheel, a pin on said wheel axially engageable in any one of said apertures in said adjustable member for locking said adjusting member on said wheel against rotation relative to each other, and a helical spring encircling said bearing means and having one end thereof fixed relative to the housing and the other end thereof connected to the adjusting member for rotating said adjusting member and urging said member into engagement with said wheel, said wheel having an aperture therein uncovering a plurality of apertures in the adjusting member whereby, when the dial has been removed, the adjusting member may be adjusted relative to the wheel with the aid of a tool inserted through the central aperture in the front wall of the housing and the aperture in said wheel.

5. In a telephone calling device having pulsing contacts and means for actuating said pulsing contacts including a rotatable wheel have a wall portion, the combination with said rotatable wheel of bearing means for supporting said wheel for rotation about its axis, housing means including a wall portion for substantially enclosing said actuating means, a motor spring for rotating said wheel and having its opposite ends operatively connected respectively to the wall portions of said housing and said wheel, and tension adjusting means for said spring interconnected between one end of said spring and its cooperating wall portion comprising a member operatively connected to said one end of said spring and engageable with said cooperating wall and angularly adjustable relative thereto about said axis, said member and said cooperating wall being shaped to have interfitting portions whereby said member may be received in any of a plurality of positions angularly disposed about said axis and relative to said cooperating wall to form a non-rotatable connection therebetween, said cooperating wall having an opening therein through which said member may be engaged by a tool and adjusted relative to said cooperating wall angularly about said axis to vary the tension of said spring.

6. In a telephone calling device having pulsing contacts and means for actuating said pulsing contacts including a rotatable wheel, a combination with said rotatable wheel of a bearing for supporting said wheel for rotation about its axis, housing means for substantially enclosing said actuating means and having an opening through which the portion of said wheel is accessible, an adjusting member engageable with and adjust-

able about its axis relative to the wheel, means for guiding said adjusting member axially relative to the wheel, a motor spring disposed about said axis and having one end thereof fixed relative to the housing and the other end operatively connected to the adjusting member for urging said member into engagement with said wheel and for stressing said member for rotation in one direction, and means on said wheel 5 and said adjusting member providing an interlocking non-rotatable engagement of said adjusting member with said wheel in any one of a plurality of positions angularly disposed about said axis, said wheel having an opening therein 10 through which said adjustable member is accessible whereby a tool may be inserted through the opening into engagement with said adjustable member to effect axial movement and rotation of the member relative to the wheel to vary the tension of said motor spring.
